GIB FOR FORMING DIES

Clarence B. Hackman, Moorestown, N.J., assignor to The Budd Company, Philadelphia, Pa., a corporation of Pennsylvania

Application December 30, 1955, Serial No. 556,534

3 Claims. (Cl. 308—3)

The invention relates to gibs, also called wiper or heel plates, which are used for accurately guiding two parts of a forming die relative to each other.

Such gibs, or wiper or heel plates, customarily consist of a solid piece of steel or bronze, which is cut from bar stock and accurately machined all around, into which grooves and holes are machined for the distribution of lubricant and for reception of attachment screws.

The object of the invention is to materially reduce cost, time and machinery for making wiper plates.

This object is achieved by the creation of a wiper plate which consists of a "shell-molded" casting of great original dimensional accuracy, which has its bearing or guide surface formed on a thin web or wall, in which the required total strength and overall thickness are achieved by marginal walls projecting transversely from said thin web, which is provided with thickened portions at the locations of holes for fastening screws and for admission of grease, and on which grease distributing channels formed as part of the original casting.

The above outlined and further objects, advantages and features of the invention will be more fully understood from the embodiment illustrated in the attached drawing and described in the following.

In the drawing:

Fig. 1 is a fragmentary, diagrammatic section through a forming die equipped with the novel wiper plates;

Fig. 2 is a fragmentary, larger-scale section of the die region including the wiper plates, the section being taken in plane 2—2 of Fig. 3;

Figs. 3 and 4 are smaller-scale inside and outside perspectives respectively of a single wiper plate;

Fig. 5 is a section, on the scale of Fig. 2, taken in plane 5—5 of Fig. 3; and

Fig. 6 is a section corresponding to and on the scale of Fig. 5 through a wiper plate and the shell mold in which it is cast.

The die, illustrated in Figs. 1 and 2 comprises an upper die or punch 11, a movable margin holder 12, and a lower die and margin holder 13. As it is customary, punch 11 and margin holder 12 are slidably guided the one relative to the other with the help of gibs or wiper plates 14 which are attached by set screws 15.

Each gib or plate 14 is a casting which comprises a thin web or wall 17 with a plane guide surface 18, marginal reinforcing walls 19 and 20, thickened portions or lugs 21 and 22 with holes 23 for the bolts 15 and holes 24 communicating upon installation with grease supply conduits 25 in the dies 11 and 12, a plane supporting surface 26 provided on portions 19 to 22 and exactly paralleling guide plane 18, and grease distribution grooves 27 in web 17 and its guide surface 18.

The formation of plate 14 to practically the exact final

2

shape and dimensions is shown in Fig. 6. Two mating shells 28 and 29 are formed (over, not shown, models) of a hardenable foundry sand mixture of great dimensional stability. The shells are provided with mating 5 projections and recesses 30 for insuring their assembly in accurately the required relative position. Upon their assembly the shells leave between them a space exactly duplicating the shape and dimensions of plate 14 with its web 17, reinforcements 19 to 22, holes 23, 24, and 10 grease grooves 27.

During casting of the metal through (not shown) inlets, the shells 28, 29 are held between flask plates 31 and 32 provided with registry pins and holes 33 and 34 and with vents 35.

Plate 14 has, upon removal of the shells 28, 29 and hardening, practically the exact dimensions of the finished plate and may call only for light grinding of its guide surface 18 and/or attachment surface 26 so as to insure smoothness of surface 18 and close tolerance in the spacing and parallelism between surfaces 18 and 26. It may furthermore be desirable to grind the long end faces on reinforcing walls 19 into close tolerance of spacing and parallelism so that the plates will fit in accurately dimensioned openings of the dies (Fig. 2) or so that two or 20 more plates may be used side by side in a row or bank (not shown). Such grinding will not amount to more than about $\frac{1}{32}$ of an inch. The short end faces on reinforcing walls 20, the holes 23, 24, and the grease grooves 27 need no machining.

From the foregoing description it will have become 30 evident that the new plate is lighter and requires negligible machining only as compared with the customary wiper plates cut off from and machined out of solid, expensive bar stock, and that it is consequently less expensive and speedier obtainable than the old plates.

The invention is not restricted to the shape and the details of the plate shown in the drawing but is susceptible to modifications and adaptations so as, for instance, to meet the individual requirements presented by dies 40 of different type, size and purpose.

What is claimed is:

1. Wiper plate for forming dies consisting of a metal casting, shell-cast closely to the ultimate shape and dimensions and having a thin web presenting on its one side with a guiding and bearing surface and provided on its other side with reinforcing wall portions extending transversely to said web and continuously along all margins of said web, said wall portions presenting a supporting surface for the plate and providing together with 45 said web an open dish-like structure, said plate having cast-in grease grooves in said web on the side of its guiding surface, and said plate being formed as part of the casting with thickened portions extending from said web in the same direction as said wall portions 50 and providing holes for attachment screws, grease conduits and the like.

2. Wiper plate for forming dies consisting of a shell-casting of close dimensional tolerance, said casting having a thin web presenting on its one side a guiding and bearing surface and provided on its other side with marginal reinforcing wall portions, said wall portions extending along all margins of said web, forming together with said web a one-sidedly open dish-like structure, and presenting a supporting surface for the plate.

3. Wiper plate according to claim 2 having formed as part of the casting thickened portions extending from said web in the same direction as said wall portions and

being provided with holes for attachment screws, grease conduits and the like.
